HIS ATTORNEY

UNITED STATES PATENT OFFICE.

JOHN TUOMEY, OF NEW YORK, N. Y.

DESIGN FOR A RADIATOR-CAP ORNAMENT FOR AUTOMOBILES.

61,403.

Specification for Design.

Patented Aug. 22, 1922.

Application filed May 28, 1921. Serial No. 473,407. Term of patent 3½ years.

To all whom it may concern:

Be it known that I, JOHN TUOMEY, a citizen of the United States, residing in the city, county, and State of New York, have invented a new, original, and ornamental Design for a Radiator-Cap Ornament for Automobiles, of which the following is a specification, reference being had to the accompanying drawing, forming part thereof.

The figure is a plan view of a radiator cap ornament for automobiles, showing my new design.

I claim:

The ornamental design for a radiator cap ornament for automobiles, as shown.

JOHN TUOMEY.
